UNITED STATES PATENT OFFICE.

ALEXIS V. DZUBAY, OF AMBRIDGE, PENNSYLVANIA.

DESIGN FOR A KITCHEN-CABINET.

SPECIFICATION forming part of Design No. 37,342, dated February 14, 1905.

Application filed December 20, 1904. Serial No. 237,718. Term of patent 14 years.

To all whom it may concern:

Be it known that I, ALEXIS V. DZUBAY, a citizen of the United States of America, residing at Ambridge, in the county of Beaver and State of Pennsylvania, have invented a new, original, and ornamental Design for Kitchen-Cabinets, of which the following is a specification, reference being had therein to the accompanying drawing.

10 This invention relates to certain new, original, and ornamental designs for kitchen-cabinets, of which the following is a specification, reference being had to the accompanying drawing, forming part thereof.

In the accompanying drawing the single figure of the drawing is a perspective view of a kitchen-cabinet embodying said design.

What I claim as new, and desire to secure by Letters Patent, is—

The ornamental design for a kitchen-cabinet, as herein shown.

ALEXIS V. DZUBAY.
